UNITED STATES PATENT OFFICE.

ALBERT RUSSO AND JOSEPH RUSSO, OF BROOKLYN, NEW YORK.

CLOTHESLINE SUPPORT.

Application filed October 29, 1924, Serial No. 746,490. Renewed June 23, 1927.

This invention relates generally to supports for clotheslines, the invention having for an object the provision of a simple and novel clothesline support of the type adapted to project the end of the clothesline inward through a window opening when the clothes are to be hung on the line or removed therefrom.

For further comprehension of the invention, and of the objects and advantages thereof, reference will be had to the following description and accompanying drawing, and to the appended claims in which the various novel features of the invention are more particularly set forth.

Fig. 1 of the drawing is a side view showing a clothesline supported by my improved device.

Fig. 2 is a plan view, a portion of the window frame on which one of the brackets is mounted being shown in horizontal section.

Fig. 3 is a fragmentary sectional view showing particularly the locking element for the outer bracket.

Fig. 4 is a fragmentary horizontal sectional view taken on the line 4-4 of Fig. 1.

Our improved device comprises a pair of brackets, one of which is adapted for mounting on the frame of a window such as 10 beside the window aperture 11, while the other is adapted for mounting on a post, wall or other support 12 at a suitable distance from the first bracket, these brackets carrying pulleys over which the clothesline 13 is looped. The bracket on the window frame comprises a plate 15 which is secured as by the screws 16 to the said window frame, and which is formed at one end with a vertically disposed cylindrical or tubular element 17, that is located in the window opening. Into this element extends a pintle 20 which is rotatably supported by said element and has a laterally extending arm 21 on its upper end. The free end of the arm has a pulley bracket 22 swiveled thereon and supporting a pulley 23. To lock the arm 21 against rotation the element 17 and pintle 20 are formed with apertures 27 and 28 that are in registry with one another, while a pin 29 may be freely suspended by a chain 30 from the bracket for insertion in these apertures.

The bracket on the support 12 comprises the angular frame 35 having an overhanging top portion to the end of which an arm 36

is pivoted as at 37, this arm carrying a roller 38 on its free end. The arm 36 is urged to vertical position by means of a coiled tension spring 39 connected at opposite ends to the arm and the bracket 35, 60 co-acting stop elements, indicated generally at 40, limiting movement of the arm under the influence of the spring.

We preferably provide a locking device for the arm 36 to lock it in its vertical, or depressed, position. To this end the arm is made hollow and a plunger rod 43 is slidably mounted in the free, or lower end thereof, and is urged upward by an expansion spring 44 bearing against the said rod. 65 From the upper end of the rod a ratchet toothed finger 45 projects laterally through a longitudinal slot 46 in the arm and engages a toothed finger 47 fixed to the bracket 35. The pulley 38 is not mounted directly on the arm 36 but on the lower end of a lever arm 48 fulcrumed as at 49 to the main arm and having a short beak or projection 50 on its upper end that extends inward through a slot 51 in the arm 36 and bears on a shoulder member or plunger 52 on the lower end of the rod 43. When the clothesline is pulled with considerable force the pulley 38 is swung forward, the rod 43 is depressed, and the arm 36 freed from the ratchet locking element 47. 70 75 80 85

In the use of my improved device the parts normally occupy the position shown in full lines. When clothes are to be hung on the line the bracket arm 21 is swung inward through the window aperture, the pull of the line acting to swing the arm 36 upward, the parts assuming the position shown in dotted lines in Fig. 1. After the clothes have been hung on the line the arm 21 is again swung outward, the spring 39 returning the arm 36 to normal vertical position. 90 95

Having thus described our invention, what we claim as new and desire to protect by Letters Patent of the United States is as follows:—

1. A clothesline support comprising a frame, a main hollow arm pivoted to said frame closed at its lower end, a spring having one end fastened to said arm, and the other end to said frame, normally urging said arm to a vertical position, said main arm having a slot therein, a plunger and a plunger rod slidably mounted in said hollow arm, a spring interposed between said 105 110 115

plunger and the lower end of said arm, normally urging the plunger and plunger rod upwards, a lever arm fulcrumed to the main arm having a short beak extending above the plunger and holding said plunger down against the action of said last-mentioned spring, a ratchet toothed finger on said frame and a toothed finger on said plunger rod, projecting through the slot and normally engaging said ratchet toothed finger, and a pulley at the free end of said lever arm.

2. A clothesline support comprising a frame element having a ratchet toothed finger thereon, a main hollow arm pivoted to said frame closed at its lower end, a spring having one end fastened to said arm, and the other end to said frame, normally urging said arm to a vertical position, coact-

ing stop elements on the said frame and arm limiting the movement of the arm at the vertical position, a plunger and a plunger rod slidably mounted in said hollow arm, a spring in said hollow arm, normally urging the plunger upwards, a lever arm fulcrumed to the main arm having a short beak extending above the plunger and holding said plunger down against the action of the latter mentioned spring, a ratchet toothed finger on said plunger rod, normally engaging said first mentioned ratchet toothed finger, and a pulley at the free end of said lever arm.

In testimony whereof we have affixed our signatures.

ALBERT RUSSO.
JOSEPH RUSSO.
